MINNOW TRAP

John B. Lewis, Beech Grove, Ind.

Application January 16, 1948, Serial No. 2,792

1 Claim. (Cl. 43—66)

1

This invention relates to a minnow trap and has for its primary object the provision of a structure which will attract and trap the maximum possible number of minnows in a given location. It has a further primary object in being able to selectively permit entrance into the trap of that size or sizes of minnows desired from relatively small sizes to large sizes.

A further primary object of the invention is to provide a structure of the type above indicated which may be relatively light and relatively inexpensively manufactured. These and many other objects and advantages of the invention will become apparent to those versed in the art in the following description of one particular form of the invention as illustrated in the accompanying drawings in which

Fig. 1 is a view in top plan and also partial section of a structure embodying the invention;

Fig. 2, a view in side elevation in partial section;

Fig. 3, a view in top plan similar to that shown in Fig. 1, but with the upper surface broken away in a different manner;

Fig. 4, a view in end elevation and partial section;

Fig. 5, a vertical section on the line 5—5 in Fig. 3; and

Fig. 6, a view in vertical section in detail on the line 6—6 in Fig. 3.

Referring to the drawings, in which like characters of reference indicate like parts throughout the several views, I form a rectangular construction having a floor 10 with upright, vertically disposed walls 11 and 12. These walls 11 and 12 are perforated or foraminous, and in the present showing, are made out of hardware cloth or wire screen, which restrict the vision of minnows therethrough. The floor 10 itself is preferably made solid, that is made out of sheet metal in order to give the desired rigidity to the entire structure.

The side walls 11 and 12 are bound around their four edges by any suitable frame-work 13, herein shown as angle irons. The upper top edge portions of the side walls 11 and 12 are interconnected by a transverse strip 14 of any suitable material, such as sheet metal. In the present showing, the ends of this strip 14 are spot-welded to the upper frame members 15 and 16 of the frame-work 13.

A mirror 60 having a mirror surface on both sides is vertically disposed centrally across between the two side walls 11 and 12 under the center strip 14. The mirror 60 is interengaged by its vertical edge portions with the side walls 11 and 12 in such manner that the lower edge of the mirror 60 is spaced a distance above the floor 10 and the top edge of the mirror 60 is likewise spaced a distance below the strip 14.

2

The spacings of these top and bottom edges of the mirror 60 are made to be such that minnows or fish if desired may freely swim across, above and below the mirror 60 when the entire structure is submerged in water.

Hinged to the strip 14 on the one side thereof is a door 17, and in like manner there is hinged to the other edge of the strip 14 the door 18. These two doors together with the strip 14 complete the enclosure across the top side of the structure between the side walls 11 and 12, this enclosure being co-extensive with the area of the floor 10 therebelow.

Referring to Figs. 1 and 4, I mount a piece of transparent material 19 to have one vertical edge at the front vertical edge of the side wall 11 and the inner vertical edge positioned toward the center of the floor 10 and spaced inwardly from its outer edge. In other words, this piece of glass 19, glass being preferable because of its rigidity compared to some other materials, although plastics of the transparent nature may be employed, is positioned in a diagonal arrangement with the side of the structure. The essential requirement of the member 19 is that it be transparent. The outer corner or edge of the member 19 is maintained in close proximity to the side 11 by means of pintles 20 and 21 so that the member 19 may be swung therearound either to the outer end of the floor 10 or inwardly around against the side 11. In like manner, a member 22 also transparent is positioned to have its forward vertical edge at the forward end of the side 12, that is the outer extreme end of that side, and is positioned there in the same manner as is the member 19 so that the member 22 may be swung around the hinged outer end. Both of these transparent members 19 and 22 occupy the entire vertical space between the floor 10 and the upper door 17 and partly under the transverse member 14 and form in effect a funnel converging toward the mirror 60. The inner opposing vertical edges of these members 19 and 22 may be swung one toward the other, Fig. 1, so that a desired spacing may be had therebetween throughout the entire height of both of these members. In practice, these members 19 and 22 may be fixed in position to give the desired spacing between those ends, or they may be yieldingly spaced one apart from the other.

To accomplish these results, the member 14, Fig. 3, is provided with a slot 23 and also a slot 24, each in an arcuate form as determined by a center of curvature located on the hinge axes of the respective members 19 and 22. The slots 23 and 24 are located adjacent the vertical inner ends of these members 19 and 22. While the members 19 and 22 may be fixed in position by any suitable means, one particular form of such fixing is shown herein as consisting of a stud 25

fixed to the upper edge of the member 19 adjacent its inner end to extend upwardly in a sliding manner through the slot 23 to receive screw-threadedly thereon a wing nut 26 from the top side of the member 14. Then in like manner a stud 27 is fixed to the member 22 adjacent its inner vertical edge to extend upwardly through the slot 24 in a sliding manner and to receive thereon screw-threadedly the wing nut 28. By running down these nuts 26 and 28 against the top side of the member 14, the members 19 and 22 may thus be held in fixed manner. In other words, by shifting the studs 25 and 27 along the respective slots 23 and 24 the spacing between the members 19 and 22 at their inner vertical edges may be varied.

To provide for the yielding spacing, the nuts 26 and 28 may be loosened to allow the respective studs 25 and 27 to slide freely in their slots 23 and 24. Then a spring 30 interconnects the two inner ends of the members 19 and 22. In the form herein shown, Fig. 1, the spring 30 is interconnected with those members 19 and 22 through eye-hooks 31 and 32 fixed respectively to the members 19 and 22.

In like manner, transparent plates 33 and 34 have their outer ends hingedly positioned toward the outer ends of the side walls 11 and 12, those ends being opposite to the ends toward which the members 19 and 22 are positioned. These two members 33 and 34 normally slope inwardly between the walls 11 and 12 to approach each other under the cross member 14 to leave the desired spacing therebetween, forming a funnel converging toward said mirror 60. These members 33 and 34 may be adjustably swung one toward the other and the spacing therebetween fixed in the same manner as was above described in reference to the members 19 and 22, the stud 35 being fixed to the member 33 and the stud 36 being fixed to the member 34 to extend vertically upwardly through the respective slots 37 and 38 provided in the member 14 and to receive from their upper ends the wing nuts 39 and 40 to screw-threadedly engage therewith. Likewise if desired, these members 33 and 34 may be yieldingly spaced apart by the spring member 30 applied in the same manner as described above in reference to the members 19 and 22.

To use the construction, the box-like structure formed in accordance with the above description is placed within the water at any suitable point where minnows or fish are to be encountered. The inclined members 19 and 22 on the one end and 33, 34 on the other end are initially adjusted to give the desired vertical spacing therebetween at their inner ends, unless they are to be left to be yieldingly spread apart through the intervention of the spring 30. Then minnows or fish approaching the device, particularly from the open ends of the structure, can see through the various members 19, 22 and 33, 34 to have their images reflected from the interior mirror 60. It seems that this reflection attracts the minnows and fish to such an extent that they will persist in trying to get through the transparent members with the result that they will nose along and inwardly of the box-like structure until they come to the inner vertical opening between the respective pairs of members and thus pass within the confines of the side walls and the top and bottom members. The spacing of the inner ends of the respective pairs of members will of course determine the size of fish or minnows which are

permitted to enter within the trap. Of course, the small ones can enter in along with the possible maximum size of fish permitted. When the members 19, 22 and 33, 34 are yieldingly spaced apart by reason of the spring 30, then should a large fish happen to strike the respective members, it might force its way on through without breaking or damaging the transparent members, and moreover when once within the trap, it can not escape back through the opening which is then smaller than it was when the fish forced its entrance between the respective pairs.

The doors 17 and 18 on the top side of the trap are normally retained in their closed position by any suitable means such as by the elastic hooks 41 and 42 which are secured to the respective doors 17 and 18 and hook down over the cross members 43 and 44 which join together the upper outer corners of the side walls 11 and 12. Where the spring 30 is desired to be used, it is initially under tension by reason of the posts which extend upwardly from the transparent members being at the inner opposing ends of the respective slots 23, 24 for example. For convenience in handling, a handle 45 is fixed to the center transverse member 14. The minnows or fish may be removed from the trap by opening either or both doors 17 and 18 and then tipping the trap up on to a corner to allow the minnows to slide out at the corner between one of the walls 11 or 12 and the respective diagonally positioned transparent member 19 or 22 at the one end or 33 or 34 at the other end.

While I have herein shown and described my invention in the one particular form, it is obvious that structural changes may be made without departing from the spirit of the invention, and I therefore do not desire to be limited to that precise form beyond the limitations which may be imposed by the following claim.

I claim:

A baitless minnow trap comprising a box having top, bottom, and side walls, the side walls being made of rough, foraminous material restricting vision of minnows therethrough; a smooth faced mirror fixed transversely across the inside of the box and spaced intermediate the box ends to define a chamber on each side thereof, said mirror being spaced by its top edge from said box top and by its bottom edge from said box bottom, to leave minnow passage openings above and below said mirror; and a transparent-walled funnel forming an entrance to said box, the walls of said funnel converging to a minnow sized opening in front of and spaced from said mirror, the sides of said funnel being smooth.

JOHN B. LEWIS.
